UNITED STATES PATENT OFFICE.

A. C. KETCHUM, OF NEW YORK, N. Y.

IMPROVEMENT IN LAMP-BURNERS.

Specification forming part of Letters Patent No. 36,717, dated October 21, 1862.

To all whom it may concern:

Be it known that I, A. C. KETCHUM, of the city, county, and State of New York, have invented a new and Improved Lamp-Burner; and I do hereby declare that the following is a full, clear, and exact description of the same, reference being had to the accompanying drawings, making a part of this specification, in which—

Figure 1 is an external view of my invention. Fig. 2 is a vertical central section of the same, taken in the line *x x*, Fig. 1.

Similar letters of reference indicate corresponding parts in the two figures.

The object of this invention is to obtain a lamp-burner which will not conduct the heat from the flame down to the body of the lamp in such a degree as to volatilize the oil too rapidly, and which at the same time will cause the flame to be supplied with air in a comparatively cool state, and in sufficient volume to insure perfect combustion, the supply of air to the flame being commensurate with the supply of vapor.

The invention is designed for burning coal-oil and other hydrocarbons, which volatilize at a comparatively low temperature and require an excess of oxygen to support proper combustion for illuminating purposes.

The invention consists in surrounding a metal wick-tube with a case or jacket constructed of porcelain, pottery, earthenware, glass, or any baked or unbaked clay or earthy substance which is a good non-conductor of heat, and using in connection therewith a cone or deflector constructed of metal, enameled both externally and internally and applied to the case or jacket, substantially as hereinafter shown and described, whereby the desired end is attained.

To enable those skilled in the art to fully understand and construct my invention, I will proceed to describe it.

A represents a metal cap, which is screwed into the top of the lamp, and B is a metal wick-tube, which is secured vertically and centrally in the cap A, projecting a trifle below it; but extending a considerable distance above it, as shown clearly in Fig. 2. The wick-tube may be of the flat kind ordinarily used in coal-oil burners, and it is surrounded by a case or jacket, C, constructed of porcelain, pottery, earthenware, glass, or other baked or

unbaked clay or analogous substance which is a good non-conductor of heat. This case or jacket C extends up nearly as high as the wick-tube B, and it is of such diameter internally that the narrow sides of the wick-tube B will be in contact with its upper part, leaving a space, *a a*, at each side for the draft or passage of air to the flame. (See Fig. 2.) The lower part of the cone or jacket is expanded in bell form, as shown clearly in Fig. 2.

D is a cone or deflector, which is constructed of metal and covered externally and internally by enamel, designated by *b b*. The cone or deflector may be of the usual form, and is provided with the ordinary slot or opening, *c*, at its upper end. To the lower edge of the cone or deflector there are attached a series of metal strips or rods, *d*, which bear or press against the outer side of the case or jacket C, and retain the case in proper position on C and without allowing it to be in contact therewith. In case a more perfect insulation of the cone or deflector from the case or jacket C should be required, the former may have rods *e* attached to it, which extend down and either rest on or clasp the top of the lamp or a plate, F, attached thereto, as shown in Fig. 1.

From the above description it will be seen that when the wick in the tube B is lighted the latter is the only part of the burner that will conduct the heat from the flame downward to the lamp. This, however, is sufficient to volatilize the oil and cause the flame to be supplied with a requisite amount of vapor. The flame is supplied with air passing up through the case or jacket C and under the lower edge or base of the cone or deflector D, (see arrows, Fig. 2,) and as C and D are both good non-conductors of heat, the flame will be supplied with air not too much rarefied, and consequently with a large volume of oxygen, and perfect combustion is obtained, as the supply of air or oxygen to the flame is commensurate with the supply of vapor, the latter being moderately supplied to the flame, for the reason previously set forth.

This burner may be used either with or without a draft-chimney. It is chiefly designed, however, to be used without a chimney.

Having thus described my invention, what I claim as new, and desire to secure by Letters Patent, is—

1. A lamp-burner having a metal wick-tube,

B, surrounded by a case or jacket, C, of porcelain, pottery, earthenware, glass, or any baked or unbaked clay or earthy substance which is a good non-conductor of heat, substantially as and for the purpose herein set forth.

2. A cone or deflector, D, constructed of metal and enameled both externally and inter-

nally, and applied to the case or jacket C, or to the lamp, substantially as and for the purposes herein shown and described.

ARCHIBALD C. KETCHUM.
